UNITED STATES PATENT OFFICE.

JOHN HARRIS, OF LAKEWOOD, OHIO, ASSIGNOR TO CARBO-OXYGEN COMPANY, OF PITTSBURGH, PENNSYLVANIA, A CORPORATION OF DELAWARE.

BLOWPIPE.

Application filed August 11, 1919. Serial No. 316,556.

To all whom it may concern:

Be it known that I, JOHN HARRIS, a citizen of the United States, residing at Lakewood, in the county of Cuyahoga and State 5 of Ohio, have invented a certain new and useful Improvement in Blowpipes, of which the following is a full, clear, and exact description, reference being had to the accompanying drawings.

10 This invention relates to blow pipes, and more particularly to the heads and tips thereof, it being the general object of the invention to improve the mode of delivering the gases to the preheating jets of such 15 pipes whereby an efficient mixture of such gases is provided and the "flashing back" or propagation of flame into the interior of the head is prevented, notwithstanding wide variations in the pressure of such mixture. 20 I accomplish the foregoing objects in and through the construction and arrangement of parts shown in the drawings forming part hereof, wherein Fig. 1 represents a side elevation of a blow pipe constructed in accordance with my invention; Fig. 2 a longitudinal central sectional view through the head of such a blow pipe and the adjacent ends of the supply tubes; Fig. 3 an elevation of the inner member of the tip; and Figs. 4, 25 5 and 6 sectional details corresponding respectively to the lines 4—4, 5—5 and 6—6 of Fig. 2.

Describing the parts by reference characters, A denotes the handle of a blow pipe 30 through which there extend the pipes 1, 2 and 3, said pipes communicating at their rear ends with passageways in a casting B to which the handle A is secured, the said casting being provided with connections for 35 the oxygen supply pipe 4 and the combustible gas supply pipe 5, the supply of oxygen to the pipes 1 and 2 being controlled by the valve 6 and the supply of combustible gas to the pipe 3 being controlled by the valve 7. 40 In addition, the supply of oxygen from the pipe 1 for cutting purposes is further controlled by the valve 8 having an operating handle 9. The parts 1—9 inclusive in their details cover no part of the invention for 45 which protection is sought in this application. For instance, the valve 8 may be constructed in the manner shown, described and claimed in my copending application No. 225,431 filed March 29, 1918.

50 At their front ends, the pipes 1, 2 and 3

are connected to the rear of the blow pipe head 10 and communicate respectively with a chamber 11 and with passageways 12 and 13 in said head. The chamber 11 is shown as cored and branched, the front ends of the 50 branches merging, as shown at 11^a, above the central head passageway 14 for the cutting oxygen. Between the branches of the chamber 11 the head is drilled, as indicated at 15, 15^a and 15^b, the bore thus provided 55 extending nearly in the same direction as the central oxygen passageway 14 and forming only a slight angle therewith. It will be noted that the portion 15 of this slightly inclined bore is threaded, while the unthreaded portion 15^a is of somewhat smaller diameter than the portion 15 and the portion 15^b is of still smaller diameter than the portion 15^a, there being an inclined seat 16 provided between the last two portions of 60 the bore. It will be noted further that the portion 15^a of said bore communicates with the delivery end of the passageway 13, while the portion 15 of said bore communicates 65 with the passageway 12.

Mounted within the three parts of said bore is a mixing plug comprising an externally threaded body 17 having a reduced projection 17^a at the upper end thereof. From the lower end of the threaded portion 70 17 of said plug there projects a reduced extension 17^b connected by a tapered seat 17^c with a still further reduced extension 17^d adapted to fit within the bore section 15^b and preferably projecting into a chamber 18 75 in said head. The plug is provided with a central passageway 19 extending therethrough and communicating at its upper end with a chamber 20 provided in the head above said plug and between the same and 80 a plug 21 which is threaded into the upper portion of the bore 15, the last mentioned plug being provided with a head 22 and with a washer 23 adapted to be compressed between said head and a seat on top of the 85 blow pipe head. The portion 17^b of said plug is provided with a pair of inclined ports 19^a communicating at their outer ends with the annular chamber surrounding said portion of the plug and at their inner ends 90 with the central passageway 19.

The tip as a whole comprises an inner member 24 and an outer member, to be referred to hereinafter. The inner member is formed as a plug having a central axial bore 110

25 which is preferably of the same diameter, throughout the major portion of its length, as the passageway 14 and adapted to register with such passageway. At its lower end 5 the bore 25 is reduced to provide a restricted discharge outlet passageway 25^a, the wall of the bore 25 being tapered at 25^b to facilitate the even flow of the cutting oxygen from the larger to the restricted portion of 10 the bore. The tip member 24 is provided with a cylindrical upper enlargement or projection 26 and below the lower end of such enlargement with an extended cylindrical enlargement 27 of smaller diameter 15 than 26 and merging at its lower end with a tapered or frusto-conical surface 28. The portions 26 and 28 are adapted to fit snugly within the outer tip member, as will be explained hereinafter, and provide means for 20 centering the inner tip member within the outer tip member as well as means whereby passageways may be provided between said members for conducting a mixture of pre-heating gases to the delivery end of the pipe. 25 Between the portions 26 and 27 the inner tip member is provided with an annular recess 29 extending therearound and adapted to form a distributing chamber with the outer tip member.

30 26^a denotes slots, which may be of any desired shape, extending radially inwardly from the outer wall of the projection 26 and providing passageways serving to conduct the mixture of gases from the distributing 35 chamber 18 to the annular distributing chamber provided by the recess 29 and the surrounding wall of the outer tip member and thence through the narrow annular chamber formed between said outer tip 40 member and the projection 27 to a series of slots 28^a extending radially inwardly from the outer surface of the tapered or frusto-conical portion 28 of the inner tip member.

Above the projection 26, the inner tip 45 member is reduced in diameter, as shown at 30, and is provided at its upper end with an enlargement 31 which is adapted to be threaded into a bore 32 provided in the head below the passageway 14, said bore extending upwardly from the chamber 18. Above the threaded portion of the inner tip member the latter is provided with a rounded head 32 adapted to engage a beveled seat 50 33 beneath the lower end of the passageway 14.

Cooperating with the inner tip member is the outer tip member 34, the latter member having a cylindrical upper end adapted to be slipped within the lower end of the 55 cylindrical chamber provided within the head and having a lower frusto-conical end 34^a. The upper and lower ends of the outer tip member form each a close fit with the portions 26 and 28 of the inner member, 60 respectively, the upper end of the outer

member being preferably flush with the upper end of the projection 26. Between the portion 27 of the inner tip member and the surrounding wall of the outer tip member, an extended annular chamber 35 is provided 70 which communicates at its upper end with the annular distributing chamber provided by the recess 29 and the surrounding wall of the outer tip member and at its lower end with the passageways formed by the slots 75 28^a. In practice this chamber will be about 1/64 inch in width or clearance and will positively prevent any propagation of flame from the slots 28^a to the chamber 29 and the passageways and chambers therebeyond 80 irrespective of variations of pressure in the mixture of preheating gases and in the combustible gas employed in such mixture.

With the parts constructed and arranged as described the operation will be as follows: The valves 6 and 7 being open, oxygen will be conducted to the pipe 2, passageway 12 and chamber 20 into the central passageway 19 of the plug 17. Combustible fluid will be conducted through the pipe 3, passageway 13, and the chamber surrounding the reduced portion 17^b of the plug into the inclined passageways 19^a and thence into the central passageway 19. The gases will be mixed in part in the lower end of the 90 passageway 19 and discharged into the chamber 18, where it is further mixed and whence the mixture is distributed to the slots 26 into the distributing chamber 29 and thence through the restricted annular 95 chamber 35 to the preheating slots or passageways 28^a. After the metal has been preheated to the desired extent, the valve 8 will be operated by the handle 9, thereby to supply cutting oxygen to the pipe 1, 100 chamber 11, passageway 14 and bore sections 25 and 25^a to the delivery end of the pipe. The construction of the plug 17 and its mode of cooperation with the oxygen and combustible gas insure a complete and 105 efficient mixture of these gases before they are delivered to the preheating slots, and the interposition of the restricted annular chamber 35 between the preheating slots or jets and the mixing portions of the head 110 positively prevent the propagation of flame to such portions of such head.

The chamber 18 enables the mixture supplied thereto by the injector plug to be distributed uniformly to the passageways provided by the slots 26, and the distributing chamber 29 enables the mixture discharged through the passageways to be distributed uniformly to and throughout the narrow annular chamber 35, which chamber conducts the gases to the slots 28^a and prevents any propagation of flame from such slots to the chamber 29 and the parts thereabove. The manner of forming the passageways 26^a and the slotted passageways 115 28^a 120

enables the inner tip member to be accurately centered within the outer tip member.

Having thus described my invention, what I claim is:

- 5 1. In a blow pipe, the combination of a head having a branched chamber for cutting oxygen and a tip having a central bore for such cutting oxygen and passageways for pre-heating gases surrounding said bore, said 70 head having a bore extending between the branches of said chamber and in approximately the direction of the first mentioned bore and also having passageways for pre-heating oxygen and combustible gas communicating with such second bore, and a plug in such second bore having a passageway extending therethrough and adapted to receive the preheating oxygen and provided with ports communicating with its passageway and adapted to conduct combustible gas thereto, said head having a chamber with which the lower end of the passageway in said plug communicates and with which the passageways in said tip also communicate. 75
- 10 2. In a blow pipe, the combination of a head having a mixing chamber therein and a bore having a reduced portion extending from said mixing chamber and an enlarged portion beyond the reduced portion with a seat interposed between such portions, and a plug adjustably mounted in said bore and having a reduced portion substantially fitting the reduced portion of the bore and a portion cooperating with said seat and forming an annular chamber with the enlarged portion of the bore and a portion beyond the second mentioned portion and fitting within the enlarged portion of the bore, the said plug having a central passageway 80 therethrough and passageways extending from said central passageway to the chamber surrounding the second portion of said plug, and the said head having a passageway communicating with the enlarged portion of the first mentioned bore beyond the end of the plug and a second passageway communicating with the said annular chamber. 85
- 15 3. In a blow pipe, the combination of a head having a mixing chamber and a bore extending upwardly from said chamber and comprising a reduced portion communicating directly with said chamber, an intermediate enlarged portion beyond such reduced portion with a seat interposed between such portions, and an enlarged threaded portion beyond said second portion, a plug having an enlarged portion threaded into the corresponding portion of the bore, an intermediate portion forming an annular chamber 90 with the intermediate portion of the bore and a reduced portion adapted to fit the reduced portion of said bore with a surface adapted to engage the seat provided between the intermediate and threaded portions of said bore, the said plug being provided with 95
- 20 a central passageway extending therethrough and with lateral passageways extending from said central passageway to the said annular chamber, and a second plug threaded into the outer end of the said bore 100 and providing a chamber with the outer end of the first mentioned plug, the said head having passageways communicating respectively with the second and third chambers. 105
- 25 4. In a blowpipe, the combination of a head having a chamber for cutting oxygen and a passageway leading from said chamber, an inner tip member having a central bore registering with said passageway, the said head being provided with a chamber 110 surrounding the upper portion of said member, an outer tip member surrounding the inner tip member and extending downwardly from said chamber, passageways for pre-heating gases being provided between said tip members and extending downwardly from the said chamber, a plug within said head and at one side of the upper end of said inner tip member and having a passageway therethrough adapted to discharge into 115 said chamber and provided intermediate of its ends with a lateral passageway communicating with its first mentioned passageway, means for delivering a gas to the first mentioned passageway of said plug at the end 120 which is remote from said chamber, and means for delivering another gas through the lateral passageway to the first mentioned plug passageway. 125
- 30 5. In a blowpipe, the combination of a head having a distributing chamber therein for preheating gases and means for delivering to such chamber a mixture of such pre-heating gases, a tip connected to said head and having a central bore for cutting oxygen 130 and a plurality of passageways extending longitudinally thereof and communicating at their upper ends with the said distributing chamber and at their lower ends with a second distributing chamber, there being 135 an elongated annular chamber within said tip, below the second distributing chamber, and restricted in width to prevent the propagation of flame therethrough, the said tip being provided with passageways extending 140 downwardly from the last mentioned chamber to the delivery end of the said tip, and means for delivering cutting oxygen to said bore. 145
- 35 6. In a blowpipe, the combination of a head having an annular distributing chamber and means for delivering a mixture of preheating gases to said chamber, a tip having its central upper portion projecting through said chamber, said tip having a central bore therethrough for cutting oxygen, and means for supplying such cutting oxygen from said head to said bore, said tip having below the said distributing chamber 150 a plurality of passageways communicating 155

at their upper ends with the said distributing chamber and at their lower ends with a second distributing chamber, the said tip having a narrow annular chamber extending 5 downwardly from the second distributing chamber, said tip having at its lower end a plurality of passageways communicating at their upper ends with the said annular chamber.

- 10 7. In a blowpipe, the combination of a head having a chamber in the lower portion thereof, a tip comprising an outer member mounted in the lower portion of said chamber and an inner member within the outer 15 member and having a central portion extending across and above the said chamber, the inner tip member being provided with a central bore and fitting within the upper portion of the outer tip member, there being a plurality of passageways formed in the inner tip member and communicating at their upper 20 ends with the upper portion of said chamber and at their lower ends with an annular distributing chamber formed in said tip and surrounding the inner member, the lower end 25 of the inner tip member fitting within the lower end of the upper tip member and being provided with delivery passages in such lower portion, there being a narrow annular 30 chamber between the said tip members and communicating at its upper end with the second chamber and at its lower end with the last mentioned passageways, and means in said head for delivering a mixture of pre- 35 heating gases to the first-mentioned chamber.
8. In a blowpipe, the combination of a head having a distributing chamber therein for preheating gases and means for delivering to such chamber a mixture of such pre- 40 heating gases, a tip connected to said head

and having a central bore for cutting oxygen and a plurality of passageways extending longitudinally thereof and communicating at their upper ends with the said distributing chamber and at their lower ends 45 with an elongated annular chamber restricted in width to prevent the propagation of flame therethrough, the said tip being provided with passageways extending downwardly from the last mentioned chamber to 50 the delivery end of the said tip, and means for delivering cutting oxygen to said bore.

9. In a blowpipe, the combination of a head having an annular distributing chamber and means for delivering a mixture of 55 preheating gases to said chamber, a tip comprising an inner member having its central upper portion projecting through said chamber and provided with a central bore there- 60 through for cutting oxygen, means for supplying such cutting oxygen from said head to said bore, said tip member having below the said distributing chamber a projection, an outer tip member having its upper end 65 surrounding and engaging said projection and its lower end surrounding and engaging the lower portion of the inner member, the said projection being provided with passage- 70 ways communicating at their upper ends with the said distributing chamber and at their lower ends with a narrow annular chamber formed between said members, said tip being provided at its lower ends with a plurality of delivery passageways for pre- 75 heating gases communicating at their upper ends with the said annular chamber.

In testimony whereof, I hereunto affix my signature.

JOHN HARRIS.
